UNITED STATES PATENT OFFICE

157,317

ELECTRICAL CORN POPPER OR SIMILAR
ARTICLE

Clare E. Applegate, Mansfield, Ohio, assignor to
Dominion Electric Corporation, a corporation
of Ohio

Application February 17, 1949, Serial No. 925

Term of patent 14 years

(Cl. D44—1)

To all whom it may concern:

Be it known that I, Clare E. Applegate, a citizen of the United States, in the city of Mansfield, county of Richland, and State of Ohio, have invented a new, original, and ornamental Design for an Electrical Corn Popper or Similar Article, of which the following is a specification, reference being had to the accompanying drawings forming a part thereof.

Figure 1 is a side elevational view of an electrical corn popper showing my new design;

Figure 2 is a top plan view;

Figure 3 is a bottom plan view; and

Figure 4 is an exploded side elevational view thereof.

I claim:

The ornamental design for an electrical corn popper or similar article, substantially as shown.

CLARE E. APPLEGATE.
